REST FOR CIGARETTES, CIGARS, AND PIPES

James J. Harkins, Wheeling, W. Va.

Application July 19, 1949, Serial No. 105,609

2 Claims. (Cl. 131—256)

1

The present invention relates to a smoker's safety appliance for cigars, cigarettes and pipes.

It is an object of the invention to provide a safe rest for lighted cigars or cigarettes formed from a single blank of material readily bendable to accommodate the blank for use separately or in combination with many different types of receptacles, such as dishes, pans, jars, drinking glasses and the like.

Another object is to provide a compound device constructed to serve as a rest for cigars and cigarettes of any length and to further serve as a brace or stall for smoking pipes.

A further object is to provide a novel rest for cigarettes and cigars adapted to be hygienically packaged for individual use in public places, whereby the usual germ infected rest of public ash trays need not be used and instead the present novel rest may be folded and mounted temporarily upon an available support.

Still a further object is to provide an inexpensive, non-breakable smoker's rest adapted for mass production by simple stamping, cutting or punching operations.

The many uses and advantages of the present invention will be more apparent after reading the following description with reference to the accompanying drawings, which illustrate several applications or uses of the invention.

In the drawings:

Fig. 1 is a perspective view showing the present invention set up for use in a tray or dish.

Fig. 2 is a longitudinal sectional view of the device illustrated in Fig. 1.

Fig. 3 is a top plan view of the same form of the invention, but showing how it may be used to serve as a pipe stall.

Fig. 4 shows a general plan view of a pattern of a blank such as may be formed into the structure of the rest shown in Figs. 1, 2 and 3.

Fig. 5 is a longitudinal view of the invention positioned to serve as a rest for cigars instead of the cigarettes shown in the preceding figures.

Fig. 6 is a side perspective view of the invention applied to an ordinary drinking glass.

Fig. 7 is a top plan view of the invention as applied to the drinking glass.

Referring in detail to the drawings and first with reference to Fig. 4, the present invention is shown in its unfolded blank form. It comprises a single strip 10 of bendable material such as light weight metal or any other suitable fire resistant material. The strip 10 is scolloped along each top and bottom longitudinal edge to form cigarette rests 11 and cigar rests 12, re-

spectively. As may be observed from the drawings, either edge may be positioned uppermost after the strip 10 has been folded into cigar or cigarette supporting position.

5 The rests 11 and 12 are each formed with little dips or sumps 13 to provide for the free flow of air below the cigarettes or cigars, thus preventing scorching and collection of moisture on the underside thereof.

10 From the material of the blank strip 10 intermediate the ends thereof and dividing the cigarette rests 11 into two separate rows is a central tab 14. This tab 14 is bendable to form a hook 15 for engagement with the rim of a glass 16, for example, see Figs. 6 and 7. Also, from the material of the strip 10 cut in from the opposite edge intermediate the cigar rests 12 is a trapezoidal shaped tab 17. The tab 17 is bendable to form an extinguishing device for cigarettes, as shown in Figs. 1 and 2. The snuff-out fin is curved upwardly to more efficiently serve to put out the cigarettes when desired and to provide a wedging action on the cigarette end.

15 In addition to the foregoing, there is cut from the material of the blank to one side of the tabs 16 and 17, a third tab 18 of specific shape, proportioned and positioned to serve as a cigarette ash separator or dropper when it is folded outwardly at right angles to the strip 10, see Figs. 1 and 2. The free end of the tab 18 is curved to form a yoke 19 to effectively separate the ashes from the cigars and cigarettes.

20 The blank 10 of Fig. 4 may be readily formed into the rest as illustrated in the other figures and prior to folding may be packaged in sealed containers, or envelopes suitable for carrying in a vest pocket. When opening the package the blank, if it is to be applied to a glass, is folded so as to have a spread greater than the chord of the mouth of the glass at the diverging ends opposite to the apex of the fold. This will assist in mounting and act as a spring to provide for a snug fit, see Figs. 6 and 7.

25 As shown in Fig. 1 the apex of the rest has a flat surface 20, which fits flush against the interior side wall of a receptacle when the hook 15 is engaged over the rim. This surface 20 has a steadyng effect on the mounting.

30 The several tabs and their respective functions are apparent from the drawings and the structure of each tab is specially arranged to provide for efficient action. For example, tab 17 which forms the extinguishing fin structure is curved upward sharply to extinguish by means 35 of a wedge-action, and tab 18 is curved into

yoke 19 to conform to the cigarette at the lighted ash end.

In actual use whether the rest is applied to a tray or glass or used separately, the V-form of the same provides means for supporting varying lengths of cigars or cigarettes as they become burned shorter and shorter. This arrangement has a safety factor and assures having an ever ready rest regardless of the length of the cigars and cigarettes to be placed thereon.

Another use shown in Fig. 3 for the rest is as a stall for a pipe, numbered 22. This keeps the pipe from capsizing and dumping its contents.

What I claim is:

1. A smoker's appliance formed from sheet material having a substantially V-shaped plan form and having means whereby the appliance may be supported upon a flat surface by the lower edges of each arm of said V, the arms of said V being of substantial height and having a pair of oppositely disposed scalloped edges with plane surfaces intermediate adjacent scallops on each edge, said plane surfaces providing spaced point contact with the flat supporting surface and means to support a cigar or cigarette in pairs of the upper of said scallops disposed upon opposite sides of the bisector of the angle of the V, with additional supporting means for the appliance at the apex of the V comprising a downwardly directed hook disposed on that portion of the V that is opposed to the direction of the arms thereof, said hook being struck outwardly and downwardly from the upper portion of the apex.

2. The combination of claim 1 wherein the 35

lower portion of the apex of the V has an inwardly and upwardly directed portion adapted to extinguish a cigarette or cigar and one of said arms of the V has an inwardly struck in and horizontally disposed portion adapted to separate ashes from a cigar or cigarette, said extinguisher, ash separator and the inner face of the other arm of the V being adapted when the same is placed upon a flat surface to support the bowl of a tobacco pipe, the stem of said pipe being disposed substantially along the axis of the V and directed away from the apex thereof.

JAMES J. HARKINS.
